his Atty.

UNITED STATES PATENT OFFICE

GUILFORD S. TURNER, OF CHICAGO, ILLINOIS, ASSIGNOR TO T-Z RAILWAY EQUIPMENT CO., OF CHICAGO, ILLINOIS, A CORPORATION OF ILLINOIS

WASHOUT PLUG

Application filed August 5, 1927. Serial No. 210,777.

The invention relates to washout plugs for boilers.

In the cleaning of boilers, it is customary to insert and operate scraping or cleaning tools through bushings after the plugs have been removed, to remove the accumulated material from the boiler, and also to insert a nozzle connected to a hose through the bushing to wash out the boiler. In this practice, it frequently occurs that the operator in the insertion of these tools will strike the seat and deform it so that the joint between the plug and the bushing will leak. This, in many instances, makes it necessary to replace the bushing or re-face the seat, in order to prevent leakage.

The primary object of the invention is to provide a washout plug in which provision is made for protecting the seat on the bushing against deformation by the tools used in cleaning and washing out the boiler.

Other objects of the invention will appear from the detailed description.

The invention consists in the several novel features hereinafter set forth and more particularly defined by claims at the conclusion hereof.

In the drawing: Fig. 1 is a section of a device embodying the invention. Fig. 2 is a section of the bushing through a pair of the oppositely disposed grooves for the application of a wrench to turn the bushing into and out of place in the boiler wall. Fig. 3 is a section illustrating a device embodying a modified form of the invention.

The invention is exemplified in a structure comprising a bushing 5 which is provided at its inner end with an exterior tapered screw thread 6, and a boiler wall 7 which is suitably threaded to receive the screw-thread 6, so that when the bushing is screwed into the wall it will be securely held therein against leakage. The bushing is provided with a series of four notches 8 adjacent its outer end to receive a suitable wrench or turning tool to facilitate the insertion and removal of the bushing. Outside of the boiler wall, the bushing is formed with an external screw-thread 9 for engagement of a corresponding internal screw-thread 10 in a cap or closure plug 11.

This cap comprises a wall 12 extending across the outer open end of the bushing, an integral flange 13 in which the screw-thread 10 is formed, and an outwardly projecting polygonal head 14 to which a wrench may be applied to turn the cap into and out of connection with the bushing. An annular groove 15 is formed in the outer end face of the bushing, and outwardly of the groove it is provided with an annular face 16 for a packing 17 which is confined and held in an annular groove 18 in the inner face of the cap. The outer end of the bushing is projected outwardly, as at 19, beyond the plane of the seat 16, and this projecting portion has an outer cylindrical surface 20 which fits into a cylindrical bore 21 in the cap.

When the boiler is to be cleaned or washed out, the cap is unscrewed from the bushing, and the gasket 17 seated in the groove 18 of the cap will be removed with the cap. As the result of projecting the annular portion or outer end of the bushing 19 outwardly beyond the plane of the face of the seat, the portion 19 serves to protect the seat 16 from injury by any of the tools inserted into the boiler through the bushing. For example, a workman roughly directing a tool into the boiler is likely to strike the end of the bushing, and when this occurs, the tool will strike the projecting portion 19 which is not utilized in forming the fluid-tight closure between the bushing and the cap. There is sufficient clearance between the outer end of portion 19 and the cap, so that any deformation, resulting from blows or abrasion from a cleaning tool, will not prevent the cap from being turned so that the gasket 17 will firmly engage the seat 16. This exemplifies a bushing of a washout plug in which the seat which is utilized to form the fluid-tight closure will be protected from deformation or abrasion likely to cause leakage of the contents of the boiler under high pressure. The cylindrical bar 21 around the projecting portion 19 serves to guide the cap into its true position with respect to the bushing, particularly as the cap approaches its closed position.

In the construction shown in Fig. 3, the bushing is provided in its outer end with an

annular groove 24 and an integral flange 25 adapted to extend around and lap the flange 26 of the cap 27. Flange 26 fits into the groove 24 and is provided with an internal screw-thread 27^a to engage an external thread 28 on the bushing. The inner end 29 of the groove 24 forms a seat for a packing gasket 30 which is engaged by the inner end of the flange 26 of the cap to form a fluid-tight connection between the cap and the bushing. In this form of the invention, the main wall of the bushing and flange 25 both serve to protect the seat 29 and gasket 30 from deformation by the tools used in cleaning the boiler.

15 By providing a protective wall or projection on the bushing in both forms of the invention illustrated, the face or seat on the bushing, utilized in forming a fluid-tight closure, is disposed so that it will not be struck by cleaning tools roughly directed into the bushing or by the tools while they are being reciprocated through the bushing in cleaning out the boiler.

20 These tools are usually of such size that they will not enter the grooves 8, but it will be understood that the latter may be omitted if desired.

25 In practice, the gasket 17 which is usually formed of copper, must occasionally be replaced. When the gasket is confined in an annular groove in the cap so that it is removable therewith, considerable difficulty has been experienced in removing the worn gasket, because in many instances tools for this purpose are not available to those engaged in the care of the locomotive. To facilitate the removal of the worn gasket, a small hole 40 is drilled through the cap 12 from the outer face thereof to the base of the groove 18, so that a small pin, nail, or strip of wire, may be inserted through the cap from the outside of the cap, to start a portion of the gasket from the groove. After a portion has been removed, the remainder can be easily pulled out of the cap.

40 The invention is not to be understood as restricted to the details set forth, since these may be modified within the scope of the appended claims, without departing from the spirit and scope of the invention.

45 Having thus described the invention, what I claim as new and desire to secure by Letters Patent is:

1. In a washout plug, the combination of a bushing provided at one end thereof with means whereby it may be secured to a boiler wall, and having an external screw-thread at its other end, a cap for closing the bushing comprising a cross wall and an annular flange connected to the marginal part of the cross wall, said flange being provided with an internal screw-thread for engagement with the external screw-thread of the bushing, said bushing and cap being provided with integral coacting annular seats, and a

5 gasket mounted against one of said seats and directly engaged by the other and operative to form a fluid-tight joint between the bushing and cap, the bushing having an annular integral portion circumferentially within 70 and projecting beyond its seat to protect said seat from injury by cleaning devices.

2. In a washout plug, the combination of a bushing provided at one end thereof with means whereby it may be secured to a boiler wall, and having an external screw-thread at its other end, a cap for closing the bushing comprising a cross wall and an annular flange connected to the marginal part of the cross wall, said flange being provided with an internal screw-thread for engagement with the external screw-thread of the bushing, the said other end of the bushing and the cross wall being provided with flat and integral coacting annular seats, and a gasket 80 mounted against one of said seats and directly engaged by the other and operative to form a fluid-tight joint between the bushing and cap, the bushing having an annular integral portion of greater length than the 85 gasket positioned circumferentially within and projecting beyond its seat and adapted to protect said seat from injury by cleaning devices, the cross wall being recessed inwardly of its seat to accommodate and receive the 90 aforesaid annular portion when the cap and bushing are in connected relation.

3. In a washout plug, the combination of a bushing provided at one end thereof with means whereby it may be secured to a boiler wall, and having an external screw-thread at its other end, a cap for closing the bushing comprising a cross wall and an annular flange connected to the marginal part of the cross wall, said flange being provided with an internal screw-thread for engagement with the external screw-thread of the bushing, the said other end of the bushing being provided with integral means forming a flat annular seat, the cross wall of the cap having formed 100 therein an annular groove, and embodying 105 a gasket fitting snugly in the groove and adapted to engage directly the seat on the bushing to form a fluid-tight joint between the bushing and cap, the bushing having an 110 annular integral portion circumferentially within 115 and projecting beyond the seat to protect said seat from injury by cleaning devices.

Signed at Chicago, Illinois, this 25th day of July, 1927.

120 GUILFORD S. TURNER.
